COMBINED HANDLE AND REEL HOUSING FOR AN EXTENSIBLE LEASH

Philip S. Rogers, 3283 Salem, Trenton, Mich.

Filed June 13, 1963, Ser. No. 75,331

Term of patent 14 years

(Cl. D38—6)

FIGURE 1 is a front perspective view of a combined handle and reel housing for an extensible leash, embodying my new design;

FIGURE 2 is a front elevational view on a reduced scale;

FIGURE 3 is a rear elevational view on a reduced scale; and

FIGURE 4 is a side elevational view thereof on the same scale as FIGURE 1.

The side opposite that shown in FIGURE 4 is the same in appearance as the side shown except for the absence of the opening for the leash.

The fragmentary broken line showing of a leash is for illustrative purpose only.

I claim:

The ornamental design for a combined handle and reel housing for an extensible leash, substantially as shown and described.
